Patented June 20, 1922.

Application filed May 16, 1921. Serial No. 470,005. Term of patent 14 years.

To all whom it may concern:

Be it known that I, GEORGE R. DEBNAM, Jr., a citizen of the United States, residing at Baltimore, Maryland, have invented a new, original, and ornamental Design for an Electric Heater, to be placed under the hood of automobiles, of which the following is a specification, reference being had to the ac-

companying drawing, forming part thereof, in which—

Figure 1 is a side elevation;

Figure 2 is an end elevation.

I claim as my invention:

The ornamental design for an electric heater as shown.
